(57) **CLAIM**

The ornamental design for a cover for washing machine and dryer, as shown and described.

DESCRIPTION

FIG. 1 is a perspective view of a cover for washing machine and dryer, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an enlarged view of portion 8 shown in FIG. 1; and, FIG. 9 is an enlarged view of portion 9 shown in FIG. 4.

The evenly spaced broken lines depict portions of the cover for washing machine and dryer that form no part of the claim. The dash-dash broken lines shown in FIGS. 1, 4, 8, and 9 depict cut off boundaries for the enlarged detail portion views that form no part of the claimed design.

1 Claim, 9 Drawing Sheets
